UNITED STATES PATENT OFFICE

161,275

REFRESHMENT STAND

Abraham H. Melcher and Robert B. Bailey,
Los Angeles, Calif.

Application March 7, 1949, Serial No. 1,256

Term of patent 14 years

(Cl. D13—1.2)

To all whom it may concern:

Be it known that we, Abraham H. Melcher and Robert B. Bailey, citizens of the United States, both residing at Los Angeles, in the county of Los Angeles, State of California, have invented a new, original, and ornamental Design for a Refreshment Stand, of which the following is a specification, reference being had to the accompanying drawings, forming a part thereof.

Figure 3 is a perspective elevation showing the other side of our refreshment stand.

We claim:

The ornamental design for a refreshment stand, as shown.

ABRAHAM H. MELCHER.
ROBERT B. BAILEY.
